UNITED STATES PATENT OFFICE

171,090

STAPLER

Robert W. Jenny, Westerly, R. I., assignor to Bostitch, Inc., Stonington, Conn., a corporation of Rhode Island

Application May 1, 1953, Serial No. 24,791

Term of patent 14 years

(Cl. D74—1)

To all whom it may concern:

Be it known that I, Robert W. Jenny, a citizen of the United States, residing in the town of Westerly, county of Washington, and State of Rhode Island, have invented a new, original, and ornamental Design for a Stapler, of which the following is a specification, reference being had to the accompanying drawing, forming a part thereof.

Fig. 1 is a side elevational view of a stapler showing my new design;

Fig. 2 is a top plan view thereof; and

Figs. 3 and 4 are elevational views of the head and handle ends, respectively.

I claim:

The ornamental design for a stapler, substantially as shown.

ROBERT W. JENNY.
